ABSTRACT OF THE DISCLOSURE

A marine propulsion system consists of two pulling units, each comprising a gear belt running in a vertical orbit positioned in a longitudinal channel in the bottom of the hull of a ship, one unit to starboard and the other to port. The hull bottom also has a longitudinal central concavity running from bow to stern. The gear belts have gear teeth on the inner surface and many scoops, closely spaced, on the outer surface. Each belt is driven by a number of toothed drums positioned within the belt orbit and meshed with the belt at both upper and lower orbit limbs. Each drum is driven by an individual electric motor. The scoops draw water from the bow and impel it toward the stern and toward the central cavity.

BACKGROUND OF THE INVENTION

This invention relates to marine propulsion systems.

Modern ships are usually driven by one or more propellers of the screw type located at or near the stern. The propellers are driven by one or several large prime movers. Vibration in these large units is frequently considerable, and precise and rapid control of the power developed by a large prime mover may be difficult.

SUMMARY OF THE INVENTION

This invention is for use on ships of any size, including the largest. The invention provides a hull bottom containing a longitudinal central slot or channel, concave downward. The bottom also has a pair of keels extending downward from the sides of the hull. The bottom also contains a pair of longitudinal propulsion channels, each one lying between a keel and the central concavity and extending for the entire length of the bottom.

The invention provides two similar endless belts, one in each longitudinal propulsion channel, each rotating in a vertical orbit, at least the lower limb of the orbit being below water. Each belt is provided with a number of scoops attached to the external surface, the scoops being angled so that, as the belt rotates, the scoops in the lower limb of the orbit impel water both toward the stern and inward toward the longitudinal center line of the bottom and into the central slot.

Thus, as the scoops push the water sternward, the reaction on the belt may be said to pull the ship forward.

Water intake is at the forward ends of the two longitudinal propulsion channels, which may therefore be termed intake ports.

The inner surfaces of the belts are provided with teeth, thus forming gear belts. Each belt is supported and driven by a plurality of toothed drums meshing with the belt; each drum is driven by an individual electric motor. All motors of each belt are controlled in concert and are driven by a prime mover such as a steam turbine connected to an alternating current generator.

One object of this invention is to provide a propulsion system which reduces turbulence below that inherent in screw propeller systems. This is a result of the much greater coupling from machine to water due to the many scoops simultaneously in contact with the water. Reduction of turbulence and maintenance of laminar flow improve efficiency.

2

Another object of this invention is to improve control by employing many, relatively small electric motors, easier to control than very large units, and by making the two belts separately controllable.

Another object of this invention is to reduce or eliminate vibration because, instead of one to four large screw propellers, the coupling to the water is provided by a large number of slowly-moving scoops.

BRIEF DESCRIPTION OF THE DRAWING

10 A further understanding of the invention may be secured from the detailed description and the drawing, in which:

FIG. 1 is a bottom view of the hull of a ship designed to contain a pair of the pulling units of this invention.

15 FIG. 2 is a bow elevation of the hull shown in FIG. 1.

FIG. 3 is a side elevation of one pulling unit.

FIG. 4 is a plan view of the pulling unit of FIG. 3, viewed from above.

20 FIG. 5 is a cross section of the pulling unit on the line 5—5, FIG. 3.

DESCRIPTION OF THE PREFERRED EMBODIMENT

Referring now to FIG. 1, the view shows a bow, 11, and a stern 12. A longitudinal center channel or slot, 13, concave downward, has the profile shown at 13 in FIG. 2. This channel runs from bow to stern. Two keels, 14 and 16, FIGS. 1 and 2, extend downward from the sides of the hull. Between keel 14 and channel 13 there is provided a longitudinal propulsion channel, 17, extending from bow to stern and having a downwardly concave cross section as shown in FIG. 2. The bow end of this propulsion channel, 18, may be termed its intake port. An identical longitudinal propulsion channel, 19, with intake port 21, is provided between keel 16 and the center channel 13. Two identical pulling units are provided in the longitudinal propulsion channels, as generally indicated in outline at 22 and 23.

One pulling unit is shown in greater detail in FIGS. 3, 4 and 5. An endless belt 24 is positioned to rotate in a vertical orbit, and preferably has such length as to extend over a major part of the length of the ship, as indicated in FIG. 1. The belt is provided on its inner surface with gear teeth 26 extending substantially the full width of the belt. The belt carries a plurality of scoops, 27, each scoop extending not quite the full width of the belt, leaving a space on each side between the end of the scoop and the edge of the belt. Each scoop is obliquely positioned on the belt and has a concave surface which, in the lower limb of the orbit, faces both toward the stern and toward the longitudinal center channel.

The belt is provided with two tensioning idlers, 28 and 29, each provided with gear teeth meshing with the gear belt. Each tensioning idler is adjustable and holds the belt taut by tension of springs, as indicated at 31 and 32.

Within the orbit of the belt there are a plurality of drums, indicated in FIG. 3 by the five drums 33, 34, 36, 37 and 38. These drums are spaced closely together. Each drum has a length substantially equal to the belt width, and carries on its periphery teeth extending longitudinally of the drum for its entire length. These teeth are designed to mesh with the belt teeth and the drum diameter is such that the drum teeth mesh with the gear belt in both the upper and lower limbs of the orbit. Each drum is individually driven by an electric motor, as indicated at 39, 41, 42, 43 and 44. All of the motors of a pulling unit are preferably controlled in concert.

Between each drum, in the lower limb of the belt orbit, there is an idler drum, indicated at 46, 47, 48 and 49. These idler drums have as their function the prevention of too much water pressure going to the top of the

unit and also the support of the lower limb of the belt. In order to accomplish these functions it is preferable that both the drum teeth and the idler drum teeth are of the female type, each tooth being a recess into which a tooth of the gear belt can fit. Each idler drum can then be faced over its cylindrical surface, except at the female tooth recesses, with a rubber-like material, thus producing a partial water seal at the contact between each idler drum and drum.

Between each pair of drums, and above the upper limb of the belt, there are smooth-faced idler rollers, as indicated at 51, 52, 53, 54, 56, 57, 58 and 59. These rollers are positioned in the spaces between the ends of the scoops and the edges of the belt. Their function is to hold the belt in position, geared to the drums in the upper limb of the orbit. These idler rollers are preferably adjustable.

I claim:

1. The combination of a marine ship having a waterline and at least one pair of similar pulling units comprising

a ship's hull having a concavity in its bottom forming a longitudinal center channel;
a pair of keels extending equally downward from the sides of said hull;
a pair of longitudinal propulsion channels, each lying between one said keel and said concavity, each said channel being defined by a watertight inclosed box;
a pair of pulling units disposed one in each said propulsion channel, said pair of pulling units being matched in power and speed;
each said pulling unit comprising

an endless belt rotatable in an orbit having a vertical plane parallel to the ship's lubber line, the lower limb of said orbit being below said waterline;

said belt carrying gear tooth means on its inner surface across its width;
scoops secured to the outer surface of said belt;
tensioning drums carrying matching teeth at the ends of said orbit;

a plurality of drums carrying matching teeth, said drums being positioned within said orbit and meshing with said belt for both supporting and powering said belt; and
an electric motor for each of said drums, each electric motor individually powering one drum, whereby the belt is so moved that in its lower limb said scoops impel water sternward.

2. The combination of claim 1 in which each of said plurality of drums meshes with said belt at both the lower and upper limbs of said orbit, and further comprising control means for powering equally the electric motors of all of said drums.

The combination of claim 1 in which said scoops are placed at an acute angle to the ship's lubber line vertical plane whereby in the lower limb the scoops not only impel water toward the stern but also inward toward said concavity, and whereby one side of each scoop pushes the water and the other side exerts a sucking, pulling effect on the water, both sides cooperating to impel the water sternward and by reaction to impel the ship forward.

4. The combination of claim 1 comprising a plurality of idler rollers smaller than said drums, one of the idler rollers being positioned between each pair of said drums and in contact with both drums of the pair, said idler roller being also in contact with the inner face of said

belt in the lower limb of its orbit, the contacts between idler roller and drums being between rubber-like material surfaces, cylindrically shaped, and the contact between idler roller and belt being gear-tooth-meshed.

5. The combination of a marine ship having a waterline and at least one pair of similar pulling units comprising

a ship's hull having a concavity in its bottom forming a longitudinal center channel;
a pair of keels extending equally downward from the sides of said hull;
a pair of longitudinal propulsion channels each lying between one said keel and said concavity, each said channel being defined by a watertight inboard box;
at least one pair of pulling units, each pair being disposed one in each said propulsion channel, said pair of pulling units being matched in power and speed;
each said pulling unit comprising

an endless belt rotatable in an orbit in a vertical plane parallel to the ship's lubber line, said orbit being elongated fore and aft, said orbit having an upper limb, and a lower limb below said waterline, said belt carrying gear tooth means on its inner surface across its width;

scoops secured to the outer surface of said belt, said scoops being placed at an acute angle to the ship's lubber line whereby in said lower limb the scoops not only impel water sternward but also inward toward said concavity;

two tensioning drums carrying belt-matching teeth within said orbit at its ends;

at least two drums carrying belt-matching teeth across the face of each drum except for a strip at each end of each drum which is cylindrically faced with a rubber-like material, said drums being positioned within said orbit and meshing with said belt at both said upper limb and said lower limb, whereby the belt's lower limb is supported against water pressure and scoop thrust and whereby the belt is powered through both lower limb contact and upper limb contact, and whereby the belt is so moved that in its lower limb said scoops impel water sternward;

at least two electric motors equal in number to the number of said drums, one of each said motors being connected for driving one of each said drums;

means controlling all of said electric motors in concert; and

idler rollers smaller than said drums but of the same length, each idler roller carrying gear teeth substantially throughout its length excepting portions at each end cylindrically faced with a rubber-like material, one idler roller being positioned between each pair of said drums and in rolling contact with both at a rubber-like material contact face, and also in meshing contact with the inner face of said belt in its lower limb.
